GRINDER FOR INVOLUTE BACON KNIFE

Raymond A. Raine, Oak Lawn, Ill., assignor to Armour and Company, Chicago, Ill., a corporation of Illinois

Filed July 17, 1957, Ser. No. 672,415

5 Claims. Cl. 51—247

This invention relates to an apparatus for the grinding of rotary knives. It is more particularly related to a portable apparatus for the sharpening of involute bacon knives.

In the conventional bacon slicing machinery the rotary blade is mounted so as to cut upon rotation in a direction perpendicular to the direction in which the bacon is passed beneath the blade. The rotary blade is normally enclosed within a guard and in many cases the guard is removable so as to expose the knife for sharpening. In at least one particular type of bacon machinery the rear portion of the guard is rigidly mounted whereas the forward and top part of the guard is movably mounted upon a hinge so as to permit the blade to be exposed. In the maintenance of the slicing machine the blade is ordinarily honed by hand at least once every two or three days by mechanics familiar with the machinery. As the cutting edge of the blade is worn down by the honing it is necessary to remove the blade from the machine and to grind down the knife edge so as to make possible a sharp rather than a blunt cutting edge. The honing of the knife edge is a very delicate operation, and consequently many blades are improperly honed and must be removed from the machine and ground again before they can be sharpened and used. The honing of the blade is a time consuming operation and therefore a costly operation even aside from the additional cost incurred when blades are improperly honed and therefore must be reground.

It is an object of the present invention to provide grinding apparatus which may be mounted upon conventional bacon slicing machinery and which can be utilized to sharpen the knife edge and therefore to accomplish the honing operation which previously has been done by hand. It is a more particular object of the invention to provide a knife sharpening apparatus which is operable upon rotatable blades whose cutting edge is of involute shape. Further objects and advantages of the invention will be seen as the specification proceeds.

In the accompanying drawings:

Fig. 1 is a vertical cross-sectional view of an apparatus embodying the novel features of the knife grinder of the present invention.

Fig. 2 is a fragmentary vertical cross-sectional view showing a mounting of the guide block and guide support.

Fig. 3 is a fragmentary end view of the grinding apparatus looking from view line 3—3 in the direction as indicated on Fig. 1.

Fig. 4 is a fragmentary top sectional view of the apparatus taken from view line 4—4 of Fig. 1.

Fig. 5 is a fragmentary view of the involute knife with the grinding wheels and guide block in operating position.

Fig. 6 is a fragmentary end view of the guide rail and grinder support.

Fig. 7 is an enlarged fragmentary vertical cross-sec-

2

tional view of the guide block and grinder wheels in operating position on the knife edge.

Fig. 8 is an enlarged fragmentary view of the relation of the various surfaces of the knife edge and of the grinder wheels.

As mentioned before, in many cases bacon slicing machinery is so designed that the upper and forward portion of the knife guard may be removed, thus exposing the knife blade immediately forward of the rear guard.

10 In the particular embodiment of the grinding apparatus of the present invention shown in the drawings, there is provided a means for attaching the grinding apparatus to this rear portion of the knife guard. Referring now particularly to Fig. 1 the permanently mounted rear knife guard of the slicing machine is designated by the numeral 11. This guard 11 extends perpendicularly from the table top 18 of the slicing table and is particularly convenient for the mounting of the present grinding machinery. In many such slicing machines the guard 11 extends somewhat higher than the knife while in other machines (as in Fig. 1) the guard 11 may not extend to the height of the knife.

The grinder of this invention is mounted upon the rear guard 11 by means of a guide rail mount 20

25 which is affixed to the rear guard 11 by means of a pressure clamp 21 as shown in Fig. 1. Attached to the guide rail mount 20 is the guide rail 22. The guide rail 22 fits immediately inside the rear guard 11 while the guide rail mount 20 extends over and around the outside of the rear guard 11. The grinder support 30 is movably mounted by means of guide wheels 26 adapted to move vertically within the grooves 24 of the guide rail 22. Referring particularly to Fig. 6 of the drawings it will be seen that the guide rail 22 is vertically aligned with the guide wheels 26 positioned on either side and adapted to move within the grooves 24. Thus it is seen that the grinding machinery framework can easily move vertically without sideways motion. The guide wheels are fixed to the grinder support 30 by means of their own axles 27.

30 A horizontal support bar 31 is rigidly mounted upon the vertical grinder supports 30. Mounted immediately beneath the horizontal support bar 31 is the block 45 which supports and maintains the alignment of the grinder wheels. An electric motor 70 or other source of power can conveniently be mounted on horizontal support bar 31 to drive the grinding wheels by means of the belt 55 and pulley 54.

35 The rotary knife blade 13 as is shown in Fig. 5 is of involute shape. It is also concave having a slight bend at point 17 on its surface. The cutting edge itself is formed by the vertical surface 16 and by surface 14, each of which is subject to the action of the grinding wheels of the present apparatus. The knife is also beveled near its cutting edge to provide a second surface 15 which makes a less acute angle with vertical surface 16 than does surface 14 (see Fig. 8). As will be seen hereafter, the surface 15 is utilized to support a guide assembly which is the means of maintaining the grinding

40 wheels in proper relationship to the knife surfaces to be ground. The vertical motion of the grinder support is controlled by a guide block and support assembly which is shown in cross-section in Fig. 2 and in an end view in Fig. 3. Greater detail of the guide block and support are shown in Fig. 7. Referring now to Fig. 7 it will be seen that the guide block 36 is mounted upon a guide block frame 38 by means of screws 39. The guide block frame 38 is mounted by means of bolts 37 to a guide support 32. On referring to Fig. 3 it will be seen that

45 the guide support 32 extends in its narrower portion 33 through the horizontal grinder support bar 31 and is affixed thereto by means of the nut 34 and upper nut 35.

The guide block 36 (Fig. 7) is notched to fit over surfaces 15 and 16 and to ride above and upon surfaces 15 and 16 without contact with the surface 14. The rotary blade as seen in Fig. 5 rotates in a counterclockwise direction. The relationship of the guide assembly, knife and grinding wheels is seen best in Fig. 5; the guide assembly is on the side of the grinding wheels immediately preceding the grinding wheels as the knife turns in its operative direction. The grinding apparatus therefore can be designed for knives rotating in either direction.

Also attached to the horizontal guide support 31 is the block 45 in which the shafts of the grinding wheels are mounted. The drive shaft 48 of the burr grinding wheel 50 is positioned in a horizontal shaft aperture and is maintained in position by means of bearings 49 which are attached to the shaft 48. The collar designated in Fig. 1 as 49a rotates and is a part of the bearing 49 which is movably fixed to the shaft 48 by means of set screw 56. At the end of the shaft 48 nearest the knife 13 there is mounted a burr grinding wheel 50. The burr grinding wheel 50 is attached to the drive shaft 48 by any convenient means such as by means of the nut 51. The grinding wheel 50 is so aligned as to present its grinding surface 52 in alignment with the vertical surface 16 of the knife 13. If desired the drive shafts 48 and 60 may be spring loaded to provide even pressure of the grinding wheel surfaces 52 and 62a on the surfaces 16 and 14 of the knife. Such spring loading may be obtained by providing a spring under tension between the block 45 and the bearings of the drive shafts.

In a second shaft aperture in block 45 there is mounted a drive shaft 60. In Fig. 1 this drive shaft is shown passing in front of and at an angle to the drive shaft 48. Drive shaft 60 is provided with bearings 61 which as in the case of bearings 49 are movably fixed to the shaft by means of set screws 61a. At the end of the shaft closest to the knife there is mounted a grinding wheel 62. This grinding wheel 62 is formed so as to bear upon the surface 14 of the knife only in the limited area comprising the surface 14.

Power may be supplied to drive the drive shaft 48 by any convenient means such as in the present preferred embodiment by an electric motor 70 mounted at the top of the apparatus upon horizontal support bar 31. Power is transmitted from this electric motor to the pulley 54 of the drive shaft 48 by means of a belt 55. The pulley 54 is affixed to drive shaft 48 by means of a collar 53 and set screw. As shown in the center of Fig. 1 and also in Fig. 4 drive shaft 48 is provided with a gear 57 which is a part of and attached to its collar 58 and is affixed to drive shaft 48 by means of set screw 59. Corresponding to this gear is the worm gear 64 of the drive shaft 60. The collar 65 forms a part of worm gear 64 and is affixed to shaft 60 by means of a set screw 66. Therefore when drive shaft 48 rotates it supplies rotary power to the drive shaft 60 by means of slidably fitted worm gear arrangement.

The position of the block 45 underneath horizontal support bar 31 may be adjusted by means of the adjustment screw 67 which is mounted in a portion 31a of the support bar 31. Upon turning the adjustment screw 67 the block 45 is caused to slide along beneath its support bar 31. To facilitate this motion the block mounting screws 46 are passed through an elongated hole in the support bar 31. Thus by loosening support screw 46 and sliding the block along beneath the bar, it may be so adjusted as to present the grinding wheels in the proper relationship to the rotary knife 13.

Variations of the particular structure may be made without departing from the operative principles of the invention. We have found it desirable in some embodiments of the machine to provide a cam attached to the face of the rotary knife about the axle 12 of the knife. The cam can be of lesser diameter than the knife but of

identical involute shape having its periphery always equidistant from the cutting edge or periphery of the knife. The guide block in this modification does not ride upon the knife edge but rather is fitted in a guide support 5 which extends down to the cam. Thus the guide block rides upon the periphery of the cam and thus maintains the grinding wheels in proper relationship to the knife edge.

In using the grinder, the apparatus is first mounted in 10 the proper position in relation to the knife. The guide block is then resting upon the knife edge or on a cam surface affixed to the knife having a guide surface equidistant from the knife edge. Power is then applied to 15 the grinding wheels and the knife is moved slowly about its axis so as to contact the grinding wheels with the portion of the knife to be sharpened. As the involute blade is rotated forward and back the block slides along the knife surface on the cam surface thus raising and 20 lowering the entire grinder framework assembly and the attached grinding wheels to maintain a proper relationship of knife edge and grinding wheels.

While in the foregoing specification specific embodiments of the invention have been set forth for the purpose of illustration, it will be apparent to the skilled in 25 the art that this invention is susceptible of many other embodiments and that many of the specific details herein may be varied widely without departing from the basic concept and scope of the invention.

I claim:

- 30 1. In a sharpening apparatus for rotary involute slicing machine knives, the combination of a grinder framework, means for movably mounting said grinder framework in automatically adjustable relationship to said slicing machine knife, a guide mounted on said grinder framework, 35 said guide being adapted to ride upon the knife edge and thereby to automatically maintain a fixed relationship between the grinder framework and the knife edge, a rotary grinding wheel mounted on said grinder framework and adapted to be rotated at a point in fixed relationship 40 to said grinder framework and thereby to said guide and to the rotary knife upon which said guide is carried.
- 45 2. In an apparatus for grinding and sharpening rotary knives of involute shape, the combination of a grinder framework, means for grinding knives, said means being 50 adjustably mounted on said grinder framework, means for movably mounting said grinder framework in automatically adjustable relationship to said rotary knife, a guide mounted on said grinder framework, said guide being adapted to ride upon and slide along the upper portion of the blade of said involute rotary knife at a 55 point which is fixed in relation to horizontal motion and the axis of said rotary knife and thereby to automatically maintain a uniform distance between the cutting edge of said rotary knife and said grinder framework.
- 60 3. In a sharpening apparatus for rotary involute slicing machine knives, the combination of a substantially vertical slide rail mounted in fixed relationship to said slicing machine and supporting a grinder framework in proximate relationship to the knife of said slicing machine, a grinder framework movably mounted upon said slide rail, means for grinding slicing machine knife blades, 65 a member adapted to maintain a uniform distance between the cutting edge of said rotary knife and said grinder framework and thereby maintaining uniform relationship between said grinding means and said rotary knife said member being substantially rigid and extending between said grinder framework and said rotary knife.
- 70 4. An apparatus for grinding a rotary knife comprising a grinder carriage, means for mounting said grinder carriage in proximate relationship to said rotary knife, said means for mounting said grinder carriage being adapted to provide for vertical motion of said grinder carriage during the grinding operation, a rotary grinding wheel, a rotatable shaft supporting said grinding wheel, means 75 for adjustably mounting said grinding wheel and said

shaft upon said grinder carriage, said means for mounting said grinding wheel and said shaft being substantially in the form of a block adjustably affixed to said grinder carriage and having apertures adapted to receive said shaft, positioning means for maintaining said grinding wheel in proper positional relationship to said rotary knife by supporting said grinder carriage upon said rotary knife at a point on said rotary knife in constant relationship to the point on the cutting edge of said rotary knife which is in contact with said grinding wheel.

5. An apparatus for grinding and sharpening involute rotary knives, comprising a grinder carriage, means for movably mounting said grinder carriage in proximate relationship to said involute rotary knives, means for grinding said involute rotary knives, said means being adjustably mounted on said grinder carriage, and a substantially

rigid positioning means mounted to said carriage and in contact with a cam surface, all points of said cam surface being substantially equidistant from corresponding points on the cutting edge of said involute rotary knives, where-

5 by said means for grinding knives are automatically maintained in proper relationship to the cutting edge of said involute rotary knives.
